UNITED STATES PATENT OFFICE.

ARLO E. RICE, OF MARCUS, IOWA.

DESIGN FOR AN ALLIGATOR-WRENCH.

18,230.

Specification for Design.

Patented Nov. 30, 1915.

Application filed August 5, 1915. Serial No. 43,891. Term of patent 14 years.

o all whom it may concern:

Be it known that I, ARLO E. RICE, a citizen of the United States, residing at Marcus, in the county of Cherokee and State of Iowa, have invented a new, original, and ornamental Design for an Alligator-Wrench, of which the following is a specification, reference being had to the accompanying drawing, forming part thereof.

Figure 1 is a side view of an alligator

wrench embodying my design, and Fig. 2 is an edge view thereof.

I claim:

The ornamental design for an alligator wrench, as shown.

ARLO E. RICE.

Witnesses:

E. L. LUNDQUIST,
C. W. CISNE.
